UNITED STATES PATENT OFFICE

113,489

DESIGN FOR AN ANIMAL BLANKET

Leo J. Du Mais, Chicago, Ill.

Application November 29, 1938, Serial No. 81,454

Term of patent 14 years

To all whom it may concern:

Be it known that I, Leo J. Du Mais, a citizen of the United States of America and a resident of Chicago, Cook County, Illinois, have invented a new, original, and ornamental Design for an Animal Blanket, of which the following is a specification, reference being had to the accompanying drawing, forming a part thereof.

I claim:

The ornamental design for an animal blanket, substantially as shown.

LEO J. DU MAIS.
